UNITED STATES PATENT OFFICE.

SAMUEL S. FRETZ, OF PHILADELPHIA, PENNSYLVANIA.

UMBRELLA AND PARASOL HANDLE.

1,101,267.

Specification of Letters Patent. Patented June 23, 1914.

Application filed May 16, 1912. Serial No. 697,651.

To all whom it may concern:

Be it known that I, SAMUEL S. FRETZ, a citizen of the United States, residing in the city and county of Philadelphia, State 5 of Pennsylvania, have invented a new and useful Umbrella and Parasol Handle, of which the following is a specification.

My invention relates to a detachable handle for an umbrella, parasol or like article, and consists in forming the stick of such article of detachable sections adapting them to be telescopically fitted together and connected and provided with means in one section for receiving the inward thrust of 10 the other section, thus firmly sustaining the latter and strengthening the joint of the sections of the stick.

Figure 1 represents a side elevation of a portion of an umbrella handle embodying 20 my invention. Fig. 2 represents a partial side elevation and partial longitudinal section thereof. Fig. 3 represents a perspective view of a detached member thereof. Fig. 4 represents a longitudinal section of another 25 embodiment of my invention, the members thereof being separated. Fig. 5 represents a perspective view of a member detached from said Fig. 4.

Similar numerals of reference indicate 30 corresponding parts in the figures.

Referring to the drawings: 1 and 2 designate sections of a tubular stick of an umbrella or parasol, the upper end of the section 2 being of greater diameter so as to 35 receive therein telescopically the lower end of the section 1. Within the section 2 is the spring-catch 3, whose nose 4 is adapted to pass through the registering slots 5 in the sections 1 and 2 respectively, thus locking 40 said sections as one. The lower portion 6 of the section 2 is of less diameter than the upper portion, forming at the places of junction of the narrow and wide diameters of said sections the tapering neck 7 which is 45 below the lower end of the section 1, its narrow diameter being below. The portion 6 of the section 1 is adapted to enter the bore of the handle 8 of the umbrella and to be secured firmly thereto in any suitable manner. Within the section 2 below the lower 50 end of the section 1, is the plug 9 which fully occupies the bore of said section and is fixed therein, it being provided with a head 10 of greater width, the same being

seated upon the inner wall of the tapering 55 neck 7 as a shoulder, whereby it is sustained firmly in the respective section and prevented from dropping therein, it being seen also that the lower terminal of the section 1 rests on said head, whereby said section is firmly sustained on the plug and the latter forms an abutment to receive the inward thrust of the sections 1 and 2 on each other in the longitudinal direction of the handle of the umbrella or parasol while the 60 sections are vastly stiffened and strengthened at the joint thereof about the neck 7, said joint otherwise being weak and liable to yield laterally and this is prevented by 65 said plug with its head.

In Fig. 4 I show the upper side of the head 10 of the plug as formed with a transversely-extending rib or ridge 11, and the lower edge of the section 1 is formed with recesses 12, the latter receiving said rib 11, 70 so as to interlock said section and plug and assist in preventing the rotation of the sections 1 and 2 one on the other, and consequent twisting of the stick or staff at the joint of the sections. It is evident that when 75 the nose 4 is pressed in to sufficient extent, the sections 1 and 2 are unlocked when they may be separated and the handle portion detached, and folded as usual with detachable handles of articles of the kind.

Having thus described my invention what I claim as new and desire to secure as Letters Patent, is:

1. In a detachable handle of an umbrella, a stick composed of a section having portions of different diameters, and a tapered neck intermediate of said portions, a plug tightly occupying the portion of the section having the smaller diameter and provided with a laterally enlarged head which is seated on the inner wall of said tapered neck, the other section of the stick being telescopically fitted in the portion of the first named section of the greater diameter and having its inner edge seated solidly on said head. 90

2. In a detachable handle of an umbrella, a stick composed of a section having portions of different diameters, and a taper neck intermediate of said portions, a plug tightly occupying the portion of the section having the smaller diameter and provided with a laterally enlarged head which is seated on the inner wall of said tapered neck, the 95 100 105

other section of the stick being telescopically fitted in the portion of the first named section of the greater diameter and having its inner edge seated solidly on said head, 5 said head being provided with a projecting rib, and the inner edge of the last named section having a recess adapted to receive

said rib when within the portion of the other section of the greater diameter.

SAMUEL S. FRETZ.
